KEY CASE

Sheldon N. Lelchuk and Stanley D. Stearns,
Miami, Fla.

Application September 19, 1952, Serial No. 310,518

5 Claims. (Cl. 70—456)

1

This invention relates to new and useful improvements and structural refinements in key cases, and the principal object of the invention is to provide a key case which is adapted to accommodate a plurality of different keys and is equipped with means for selectively and individually projecting such keys into an operative position.

One important feature of the invention resides in the provision of means for individually locking and sustaining the keys in their retracted position until such time as the locking means are manually released, while another feature of the invention resides in the provision of means for simultaneously retracting one or more of the keys which have been projected.

Some of the advantages of the invention reside in its simplicity of construction, in its efficient and convenient operation, and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a front elevational view of the invention with the keys retracted;

Figure 2 is a front elevational view of the invention with one of the keys in its projected position;

Figure 3 is a side elevational view of the device shown in Figure 1;

Figure 4 is a top plan view of the device shown in Figure 1;

Figure 5 is a vertical sectional view of the key case on an enlarged scale, illustrating one of the key holders in its retracted position;

Figure 6 is a vertical sectional view, similar to that shown in Figure 5, but illustrating one of the key holders in its projected position;

Figure 7 is a vertical sectional view, taken substantially in the plane of the line 7—7 in Figure 5;

Figure 8 is a fragmentary sectional view illustrating the manner in which the key holder locking means are released;

Figure 9 is a fragmentary sectional detail, taken substantially in the plane of the line 9—9 in Figure 5;

Figure 10 is a perspective view of the key holder retracting means, and

Figures 11 and 12 are elevational views of two different key holder guides used in the invention.

2

Like characters of reference are employed to designate like parts in the specification and throughout the several views.

Referring now to the accompanying drawings in detail, the invention consists of a key case which is designated generally by the reference character 10 and embodies in its construction a vertically elongated housing 12 including a top wall 14, a side wall 16 and having an open bottom 18, as shown.

The side wall 16 is provided with a vertical slot 20, while the top wall 14 is provided with a plurality of relatively short, transversely and longitudinally staggered slots 22.

15 A plurality of vertically elongated key holder guides 24 are secured at their lower ends by welding, or the like, indicated at 26 to the inner surface of the side wall 16 adjacent the open bottom 18, the upper ends of the guides 24 being equipped with horizontally extending members 26a, 26b, 26c which have provided thereon upwardly projecting stems 28 equipped with hand actuated knobs 30.

20 The stems 28 project upwardly through the top wall 14 of the housing 12 through the respective slots 22 and it will be apparent from the foregoing that when any one of the knobs 30 is manually shifted from the position shown in Figures 5 and 6 to the position shown in Figure 8, the associated guide 24 will be shifted away from the side wall 16. However, the guides 24 are formed from resilient material and are biased to a position adjacent the side wall, as shown in Figures 5 and 6.

25 Each of the guides 24 consists of a pair of spaced parallel rods 24a which are connected at their lower ends to a single rod 24b of an arcuate configuration, it being the resiliency of the rod 24b which urges the entire guide toward the side wall of the housing.

30 An elongated key holder 32, provided with a slot 34 to slidably receive the rods 24a is positioned on each of the guides 24 the key holder also being formed with an elongated, split opening 36 to removably receive a key 38.

35 By virtue of this arrangement, the several key holders and the associated keys are slidable vertically on the respective guides 24 from a retracted position, shown in Figures 5 and 8 to a projected position shown in Figure 6. It is to be noted that the slot 34 in each key holder is of such length as to substantially correspond to the spacing of the guide rods 24a, so that when the key holder is in engagement with the two guide rods, it is sustained in a substantially hori-

zontal position as shown. However, when the key holder is permitted to slide downwardly to the rod 24b, it is also permitted to swing downwardly to a projected depending position, as shown in Figure 6. It is to be noted that in that position the key 38 attached to the projected key holder is entirely exposed for use, while in the retracted position as shown in Figure 5, the key holder as well as the associated key are fully concealed in the housing.

A plurality of cam shaped lugs or detents 40 are provided on the inner surface of the housing side wall 16 to supportably engage the respective key holders 32 and retain the same in their retracted position, but when the knobs 39 are selectively and individually actuated by pushing the same away from the side wall 16, the appropriate key holder or key holders are disengaged from the detents 40 and are permitted to slide downwardly on their respective guides 24 so as to project the appropriate, selected keys. The position of a key holder disengaged from its locking detent is clearly shown in Figure 8.

A compression spring 42 is provided on one of the rods 24a of each key holder guide 24 so as to urge the associated key holder to its projected position, and means are also provided for simultaneously retracting any of the projected keys.

These means consist of a transversely extending retracting bar 44 which is formed integrally with a guide 46 slideable in the aforementioned slot 20, while a shank 48 on the guide 46 projects outwardly through the slot and carries an actuating knob 50.

When the several key holders 32 are in their retracted positions, the bar 44 underlies the same, as shown in Figures 5 and 8, but when any one of the key holders is manually released, the resiliency of the associated spring 42 not only urges the appropriate key holder downwardly on its guide, but also slides the bar 44 downwardly in the slot 20 to the position shown in Figure 6.

Thereupon, when the projected key or keys are to be retracted, they are simply swung upwardly to a horizontal position by manual means, thereby compressing the spring 42 during this movement so that the key holder or key holders are disposed above the bar 44 as the bar appears in Figure 6, and by simply sliding the knob 50 upwardly on the housing, the bar 44 will simultaneously retract one or more of the projected key holders and keys to the retracted position shown in Figures 5 and 8.

Suitable detents 52 may be struck inwardly from the side wall 16 of the housing so as to engage the underside of the bar 44 in its retracted position and resist the sliding thereof downwardly until such time as such sliding is effected under the pressure of any one of the springs 42 when one or more of the keys are manually released.

It is to be noted that the various knobs 39 are disposed in longitudinally as well as transversely staggered relation so that they are readily accessible for individual, selective use. Of course, the staggered disposition of the knobs is afforded by the provision of the guide members 26a, 26b and 26c of different lengths.

It is to be also noted that when the key holders are in their projected positions, the associated keys become fully exposed and may be removed from or installed on the key holders, as desired.

It is believed that the advantage and use of the invention will be clearly understood from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

1. A key case comprising a housing having an open bottom and including a side wall and a top wall, a plurality of key holder guides extending from the bottom to the top of said housing, a plurality of key holders slideable on the respective guides between projected and retracted positions, resilient means provided on said guides for urging the key holders to the projected position, detent means in said housing for locking the holders in the retracted position, means on the top wall of said housing for selectively and individually shifting the guides away from said detent means for releasing the key holders, and means provided on the side wall of the housing for simultaneously returning released key holders to the retracted position.
2. In a key case, the combination of a housing having an open bottom and including a side wall and a top wall provided with a slot, an elongated key holder guide secured at its lower end to said side wall at the open bottom of the housing, the upper end of said guide being movable in said slot toward and away from the side wall, a key holder movable upwardly and downwardly on said guide, a detent on said side wall engageable with said holder for locking the same in its upwardly slid position, and a manually actuatable knob provided at the upper end of said guide for moving the same away from the side wall to disengage said holder from said detent.
3. The device as defined in claim 2 wherein said guide is resiliently biased toward said side wall.
4. The device as defined in claim 2 together with resilient means on said guide for urging said holder downwardly.
5. The device as defined in claim 2 together with manually actuatable means provided on said side wall and engageable with said holder for moving the same upwardly on said guide.
